DRAWBENCH APPARATUS

John S. Miller, Poland, Ohio, assignor to The McKay Machine Company, Youngstown, Ohio
Filed June 25, 1963, Ser. No. 290,454
9 Claims. (Cl. 72—284)

The present invention relates to a drawbench, more particularly to a drawbench of the hydraulic type and to sub-assemblies particularly adapted for use therewith, and the principal object of the invention new and improved devices of the character described.

As generally known in the trade, a drawbench is a device for drawing elongated stock, such as a rod, through a die in order to effect a transverse reduction in the size of the stock. In many cases, a powerful hydraulic cylinder is employed to pull the stock through the die.

Since the stock to be drawn is initially of considerable length; since such length is materially increased as a result of the drawing operation; and since a hydraulic cylinder having a stroke at least as long as the stock after drawing must be employed, the normally constructed drawbench tends to require a considerable length of floor space. For example, and as will later appear, a conventional drawbench for drawing 20 foot stock to a length of 25 feet will require more than 70 feet of floor space. In contrast, by the use of the present invention, a saving of about 20 feet of floor space length can be effectuated with no decrease in stock capacity.

Additionally, since the present invention utilizes the greater force application effectiveness of a hydraulic cylinder on its out-stroke rather than on its in-stroke as is conventional, a smaller diameter hydraulic cylinder and/or less hydraulic pressure and volume may be employed with considerable cost savings. These and other advantages will readily become apparent from a study of the following description and form the drawings appended hereto.

In the drawings accompanying this specification and forming a part of this application there is shown, for purpose of illustration, an embodiment which the invention may assume, and in these drawings:

FIGURE 1 is a side elevational view of a preferred embodiment of the invention,

FIGURE 2 is a top plan view thereof,

FIGURE 3 is an enlarged plan view, partially in section, and generally corresponding to the line 3—3 of FIGURE 1,

FIGURE 4 is an enlarged plan view, partially in section, and generally corresponding to the line 4—4 of FIGURE 1,

FIGURE 5 is a still further enlarged, fragmentary sectional view generally corresponding to the line 5—5 of FIGURE 2,

FIGURE 6 is a sectional view generally corresponding to the line 6—6 of FIGURE 4,

FIGURE 7 is a reduced size, generally diagrammatic view similar to FIGURE 1, and

FIGURE 8 is a view similar to FIGURE 7 and to the same scale but of prior art apparatus.

With reference to FIGURES 1 and 2 and for convenience of disclosure, the apparatus herein illustrated may conveniently be divided into a die station A, a stock entry portion B to the left of the die station, and a stock drawing portion C to the right of the die station. Associated with the stock entry portion B is a stock entry table 10 and interposed between the latter and the die station A is a stock entry carriage 11 having a relatively short path of travel toward and away from the die station. To the right of the die station, the stock drawing portion C provides a draw carriage 12 shown adjacent

2

the die station but shiftable from such position to the extreme right-hand end of the apparatus. As will later be disclosed in greater detail, each carriage 11, 12 is provided with jaws for gripping the stock to be drawn 5 through the die station A.

In brief, operation of the apparatus thus far described will be as follows: The stock to be drawn will be placed on the stock entry table 10 with its right-hand end adjacent the die station. The stock entry carriage will next grip the stock and will then be shifted to the right to force the stock end through the die station far enough to permit it to be gripped by the stock drawing carriage 12. After the stock drawing carriage 12 has gripped the stock, such carriage will be shifted to the right to draw the remainder of the stock through the die station thus completing the drawing operation. With the drawing operation completed, the stock will be released by the carriage 12 for removal thereof from the apparatus. Both carriages may now be returned to the positions shown in FIGURES 1 and 2 and the foregoing operations repeated on another piece of stock.

Still referring to FIGURES 1 and 2, the means for effecting movement of carriage 12 to the right comprises a pair of elongated fluid cylinder assemblies 13 in spaced-apart, side-by-side relation. As will later be disclosed in greater detail, the right-hand end of each cylinder assembly is secured to respective upright ears 14 of a frame structure 15 whose other end provides upright ears 16 forming a part of the die station A. The left end of each cylinder assembly 13 is supported on a stanchion 17, similar stanchions 18 being interposed between stanchions 17 and the frame 15 and spaced along the cylinder assemblies to support the latter. Stanchions 18 may also conveniently be employed to support the stock entry table 10.

Turning now to FIGURE 5 wherein the left-hand end of one of the cylinder assemblies 13 is illustrated, it is to be understood that both cylinder assemblies are preferably identical and thus only one need be shown and described in detail. As presently disclosed, cylinder assembly 13 comprises an elongated cylinder barrel 19 whose right-hand end is anchored to a frame ear 14 by means later to appear. The left-hand end of the barrel 19 is suitably closed by an end plug 20 to which is connected a conduit 21 through which fluid may pass into and out of the cylinder barrel.

Slidable in the cylinder barrel is a piston 22 carrying suitable sealing rings 23 and secured to the right-hand end of piston 22 is a tubular piston rod 24. In the present embodiment, a stud 25 has an enlarged end 26 suitably anchored to the piston rod 24 and a shank portion 27 extending through an enlarged central aperture 28 in the piston. Such aperture is reduced in size at the left of the piston and an O sealing ring 29 prevents the escape of fluid between the piston and the stud. The extreme left-hand end of stud 25 is threaded to receive a pair of nuts 30 which retain the piston assembled on the stud.

It is an important feature of the present invention that the ends of piston 22 are spherical and are seated against respective complementarily formed washers 31, 32 assembled over the stud shank. This arrangement permits the piston rod 24 to deflect transversely without exerting a force on the piston tending to cock it in its cylinder bore. Obviously, because of the great length of the piston rod, it will have a tendency to deflect, even of its own weight, a small but significant amount.

Since piston rod 24 is subjected to compressive forces, rather than tension forces, during the stock drawing operation, it is important that the piston rod be of maximum size to resist any tendency to buckle. Accordingly, the piston rod is herein shown to have a transverse size but slightly smaller than the bore of the cylinder barrel 19. With such a piston rod to cylinder bore relationship and

with such a long piston rod, transverse deflection of the rod could cause it to rub along and scratch the cylinder barrel. To eliminate this possibility, the piston rod is presently covered with sleeves 33 of non-ferrous, relatively soft material in end-to-end, abutting relation. Such sleeves may be formed of a suitable plastic or a soft metal such as babbitt. Although not shown, a slight operating clearance will be provided between the exterior of the sleeves 33 and the bore of the cylinder barrel 19.

Referring now to FIGURE 3, the right-hand end of the cylinder barrel 19 is externally threaded to receive a shouldered sleeve 34 and the latter is tightly clamped against the frame ear 14 by means of a nut 35 threaded on the sleeve. Seated against the right-hand end of sleeve 34 and concentric with the cylinder barrel 19 is a hollow piston rod 36 through which the piston rod 24 passes. Here again, operating clearance over the piston rod sleeves 33 will be provided. Hollow piston rod 36 is firmly clamped against the sleeve 34 by means of a split collar 37 bolted to the frame ear 14 and having a radially inwardly projecting flange seated in an annular groove formed in the rod 36.

For a purpose later to appear, the end of hollow piston rod 36 adjacent the cylinder barrel 19 has an enlarged bore portion in which is seated a flexible, annular wiper member 38 encircling and engaged with the exterior of the covered piston rod 24. Adjacent this wiper and on the side thereof away from the cylinder barrel 19 is an annular recess 39 surrounding the piston rod 24. A conduit 40 places recess 39 in communication with a source of pressurized fluid.

The right-hand end of the hollow piston rod 36 is reduced in diameter and passes through a close-fitting aperture in a frame ear 16 and is externally threaded to receive a nut 41 which clamps the rod firmly in position. Enclosing the right-hand end of hollow piston rod 36 is an axially elongated collar 42 bolted to the ear 16. The interior of collar 42 carries an annular wiper member 43, similar to 38, and provides an annular recess 44, similar to recess 39. A drain conduit 45 carries fluid away from recess 44 and returns it to the pressure source connected to the previously described conduit 40.

Turning next to FIGURE 4, it will be noted that the piston rod 24 extends beyond the die station A and is secured to the draw carriage 12 by any suitable means, such as, for example, the flat-head capscrews 46. Carriage 12, therefore, spans the piston rods 24 of the two cylinder assemblies 13 (see FIGURE 6) and ties them together for unitary movement.

In order to guide the piston rods 24 as they are shifted to the right from the position seen in FIGURES 3 and 4, each is contained within an elongated, tubular member 47 which provides a small radial operating clearance over such piston rod. Such members 47 serve a multiple purpose in that they not only function to guide the rods, but also support them against buckling and protect them from dirt and the like. As best seen in FIGURE 4 wherein one of the members 47 is shown in section, each member is secured to a respective collar 42 by means of a suitable collar 48 and each extends therefrom the full length of the apparatus drawing portion C and has its free end supported by an overhanging stanchion 49 (FIGURES 1, 2 and 6). Additional, identical stanchions 50 are interposed between the stanchion 49 and the frame 15 and are spaced along the members 47 for adequate support thereof. As best seen in FIGURE 6 and since the carriage 12 extends between the ends of the piston rods 24, the facing sides of the tubular members 47 are cut away to pass the carriage. At each of the stanchions 50, 49, a conduit 51 provides for the return of oil in a manner similar to the conduits 45 previously described.

Returning once again to FIGURE 3, it will be noted that the hollow piston rod 36 has an integrally formed piston 52 intermediate its ends. Slidably along the piston rod 36 and cooperable with the piston 52 is a cylinder

barrel 53 having the usual seal structure at each end for sealing about respective, adjoining piston rod portions. Conduits 54, 55 provide for passage of fluid to the interior of the bore of cylinder barrel 53 on opposite sides of the piston 52. From the foregoing it will now be clear that the piston rod 36, piston 52 and cylinder barrel 53 constitute a cylinder assembly which is reversed from the ordinary assembly in that the piston and its rod are held stationary while the cylinder barrel is shiftable axially of the piston rod. The cylinder barrel 53 and all the other associated parts hereinabove described are, of course, duplicated on the opposite side of the apparatus.

The previously mentioned stock entry carriage 11 is herein shown integral with the cylinder barrels 53 and is provided with opposed jaws 56 for gripping the stock S shown in phantom lines. Although not shown, a suitable actuating mechanism may be employed to effect jaw movement to grip and release the stock. Similarly, and with reference to FIGURE 4, the stock drawing carriage 12 will be provided with opposed jaws 57 for gripping the stock. Here again, suitable means may be provided for effecting jaw movement to grip and release the stock. Completing the structure and referring to FIGURES 3 and 4, a die 58 will be suitably mounted at the die station A. For example, the die may carry opposed lugs 59 which fit closely within respective slots formed in the frame ears 16.

With the parts positioned as illustrated in FIGURES 1 through 5 and with the carriage jaws 56, 56 and 57, 57 separated, a piece of stock S will be pushed between the jaws 56 of the stock entry carriage 11 and into abutment with the die 58. Jaws 56 will now be actuated to clamp the stock and fluid under pressure admitted through the conduits 55 to cause the cylinder barrels 53 and the associated carriage 11 to move toward the die 58. Movement of carriage 11 as above described will force the end of the stock through the die 58 far enough so that the stock can be gripped by the carriage jaws 57 as illustrated in FIGURE 4. Jaws 57 will next be actuated to grip the stock while the jaws 56 will be released therefrom. Carriage 11 may, if desired, be returned at this time to the position seen in FIGURE 3 by admitting fluid pressure through conduits 54.

With the stock being gripped by the jaws 57, fluid under pressure will be admitted through conduits 21 to thus shift the pistons 22, the piston rods 24 and the carriage 12 to the right. Movement of the carriage 12 in this direction will draw the stock through the die 58 as will be understood. When the entire length of stock has been drawn through the die 58, jaws 57 will be shifted to release the stock whereupon the latter can drop free of the apparatus.

During the foregoing operational sequence, oil under pressure will be continuously supplied through the conduits 40 to each of the recesses 39. Such oil will then flow along the exterior of each piston rod 24 to lubricate the latter as they move to the right. The majority of such oil will be recovered by the recesses 44 and the conduits 45; however, any excess oil drawn along with the piston rods will be returned to its source through the conduits 55 at respective stanchions 50, 49.

Following the drawing operation hereinabove described, the carriage 12 will be at the extreme right-hand end of the apparatus and, since the cylinder assemblies 13 which effect its movement are single acting, separate means (not shown) will be employed to return this carriage to the position seen in FIGURE 4. This may readily be accomplished by, for example, a fluid cylinder having cable connection with the carriage or by an electric motor having driving connection with a chain which is in turn connected to the carriage. Various other expedients may as well be used, it being understood that relatively little force will be required to so return the carriage.

Regardless of the means used to return the carriage, it will be understood that such operation causes the piston rods 24 to move to the left, the wipers 43, 38 wiping the

rods free of any foreign matter and the continuous oil flowflushing the rods and carrying away any such foreign matter. Accordingly, as the piston rods are retracted into their cylinder barrels 19, they will be cleansed so as not to draw foreign matter into the barrels. With the carriage 12 positioned once again as seen in FIGURE 4, another stock drawing cycle may be commenced.

As earlier mentioned, a major advantage of the present drawbench over those heretofore known is a considerable reduction in space requirements. This is accomplished by the hereinabove disclosed disposition of the draw carriage cylinder assemblies on the entry side of the die stand, or station, in superposed relation with the entry table, rather than on the exit side of the die stand.

FIGURE 7 illustrates the present invention wherein there is shown a drawbench for receiving 20 foot lengths of stock and for drawing such stock to a length of 25 feet. In order to draw the stock to a length of 25 feet, carriage travel of 25 feet will be required (ignoring, for present purposes, a certain amount of carriage overtravel which must normally be provided). With an assumed carriage travel of 25 feet, each carriage shifting cylinder must have a travel of 25 feet. Note in FIGURE 7 that the 25 foot stroke carriage actuating cylinder is disposed on the entry side of the die stand in superposed relation with the 20 foot entry table. Thus, the apparatus requires a total of 55 feet of floor space if the die stand is assumed to require 5 feet of space.

In contrast and referring to FIGURE 8, prior-art apparatus of the same capacity requires the same 20 foot entry table, the same 5 foot die stand, the same 25 foot carriage travel, and the same 25 foot stroke, carriage actuating cylinder. However, since the prior-art, carriage actuating cylinder is disposed on the exit side of the die stand, a total of 75 feet of floor space is required. Clearly, this is 20 feet more floor space than is required by the presently disclosed, novel apparatus.

In view of the foregoing it will be apparent to those skilled in the art that I have accomplished at least the principal object of my invention and it will also be apparent to those skilled in the art that the embodiment herein described may be various changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. A drawbench comprising a fixed die station having a stock entry side and a stock exit side, first and second carriages on the entry and exit die station sides respectively and each having means for gripping the stock, and a pair of concentric, fluid cylinder assemblies for respectively urging said first carriage toward said die station to push one end of a length of gripped stock therethrough and for urging said second carriage away from said die station to pull the remainder of the length of gripped stock therethrough.

2. The construction of claim 1 wherein each fluid cylinder assembly comprises a cylinder barrel, a piston within each cylinder barrel and a piston rod connected to each piston, and wherein the cylinder barrel of each assembly is disposed on the entry side of said die station.

3. The construction of claim 2 wherein the piston rod of one assembly and the cylinder barrel of the other assembly are fixed against axial movement, and wherein the cylinder barrel of said one assembly and the piston rod of the other assembly are connected to said first and second carriages respectively for effecting movement thereof.

4. The construction of claim 3 wherein the piston rod of said one assembly is hollow and wherein the piston rod of said other assembly extends therethrough for connection to said second carriage.

5. The construction of claim 4 wherein a tubular mem-

ber is in axial alignment with the piston rod of said other cylinder assembly for receiving and supporting such rod against lateral deflection when the latter is projected outwardly of its cylinder barrel, and wherein the piston rod of said one cylinder assembly is interposed between said member and the cylinder barrel of said other assembly.

6. A drawbench comprising a fixed die station having a stock entry side and a stock exit side, first and second carriages on the entry and exit die station sides respectively and each having means for gripping the stock, two hydraulic cylinder assemblies in side-by-side relation on opposite sides of the path of stock travel through said die station for urging said first carriage toward said die station to push one end of a length of gripped stock therethrough and for urging said second carriage away from said die station to pull the remainder of the length of gripped stock therethrough, each cylinder assembly providing a pair of concentric cylinder barrels disposed on the entry side of said die station, a piston within each barrel and a piston rod connected to each piston, one of the piston rods and one of the cylinder barrels of each assembly being fixed against axial movement and the other piston rod and the other cylinder barrel of each assembly being respectively connected to said second and first carriages for effecting movement thereof, and a pair of tubular members in axial alignment with respective, said other piston rods for receiving and supporting such rods against lateral deflection during movement of said second carriage away from said die station.

7. A drawbench, comprising a fixed die station having a stock entry side and a stock exit side, a draw carriage on the exit side of said die station and having means for gripping the stock, a hydraulic cylinder assembly including a cylinder barrel on the stock entry side of said die station and a piston rod extending from one end of said barrel and directly connected to said carriage for moving the latter away from said die station to draw the stock therethrough, said piston rod being stressed in compression during such carriage movement and being slightly smaller in transverse section than the bore of said cylinder barrel and low friction, non-marring material covering said piston rod to insure against scratching of said bore by said rod, a tubular member which partially encloses said rod and which supports the same against lateral deflection when it is projected outwardly of said cylinder barrel, and means at said one cylinder barrel end for bathing said piston rod and the interior of said tubular member to remove deleterious material from said piston rod prior to retraction thereof into said cylinder barrel and to remove such deleterious material from said tubular member.

8. A drawbench, comprising a die having a stock entry side and a stock exit side, a stock gripping jaw on the exit side of said die, means for pushing the forward end of the stock from said entry side through the die opening and to project from said exit side, means for engaging said gripping jaw on the projecting portion of said stock, and a fluid cylinder located on said entry side and having a piston rod connected to said stock gripping jaw for pushing the latter in a direction away from said exit side and thereby draw the remainder of the stock through said die.

9. A drawbench, comprising a die having a stock entry side and a stock exit side, first and second stock gripping jaws located on said entry and exit sides respectively, means for engaging said first gripping jaws on the stock inward of its forward end, a first fluid cylinder for moving said first gripping jaws toward said die an amount to push the forward end of the stock from said entry side through the die opening and to project from said exit side, said first gripping jaws thereupon being released from said stock, means for engaging said second gripping jaws on the projecting forward end of said stock, and a second fluid cylinder located on the entry side of said die and having a piston rod connected to said sec-

ond gripping jaws for pushing the latter away from said exit side and thereby draw the remainder of the stock through said die.
